UNITED STATES PATENT OFFICE.

HANS CHRISTIAN, OF VIENNA, AUSTRIA-HUNGARY.

ADJUSTABLE COAT-HOLDER.

SPECIFICATION forming part of Letters Patent No. 364,803, dated June 14, 1887.

Application filed October 23, 1886. Serial No. 217,058. (No model.)

To all whom it may concern:

Be it known that I, HANS CHRISTIAN, of Vienna, Austria-Hungary, have invented a new and Improved Adjustable Coat-Holder, of 5 which the following is a full, clear, and exact description.

The object of my invention is to provide a new and improved coat-holder which is simple and durable in construction and adjustable to 10 any size.

The invention consists of two shoulder-supports adapted to slide on a wire.

The invention also consists of various parts and details and combinations of the same, as 15 will be fully described hereinafter, and then pointed out in the claims.

Reference is to be had to the accompanying drawings, forming a part of this specification, in which similar letters of reference indicate 20 corresponding parts in all the figures.

Figure 1 is an under side view of my improvement. Fig. 2 is a cross-section of the same on the line A B of Fig. 1; and Fig. 3 is a perspective view of the under side of one of 25 the supports.

The shoulder-supports *a a*, preferably made of sheet metal, are each formed to correspond in shape to the relative part of the garment, and each is provided on its under side with 30 ears or lugs *b b*, punched and formed from a part of the support *a*. A wire, *c*, is bent into the shape shown in the drawings, and its two outer parallel bars pass through the lugs or ears *b*, and thus carry on each side of the wire *c* the 35 supports *a a*. The wire *c* is formed in its center into a loop, *f*, on which is placed the swivel-hook *d*, and the ends of the said wire *c* are each formed into a hook, *e*, which projects from the front of the device and serves for 40 holding other articles, such as hats.

It will be seen that the shoulder-supports *a* can be moved inward and outward on the two parallel bars or wires *c*, so as to correspond to the width of the garment at its shoulders, and as the shape of each support *a* is curved 45 to the form of the shoulder part of the garment it is evident that the latter cannot get out of shape while suspended.

Garments when wet are very apt to lose their shape when suspended from holders now 50 generally in use; but this is entirely avoided by my improved coat-holder having the adjustable shoulder-supports *a*.

Having thus fully described my invention, I claim as new and desire to secure by Letters 55 Patent—

1. As an improved article of manufacture, a hanger comprising the single length of wire bent to form two sets of parallel bars, *c c*, the ends of the wire being coiled at the inner ends 60 of the parallel bars and bent outward to form two hooks, *e e*, the rounded shoulder-supports *a a*, having eyes or ears *b b* on their under faces, through which pass the parallel arms, and a suspension device, substantially as set 65 forth.

2. A coat-hanger consisting in the wire *c*, coiled at its center, as shown at *f*, and inclined downward, then outward, and bent to form the parallel bars, the ends of the wire being coiled 70 around the body of the wire at the inner ends of the parallel bars, the rounded shoulder-supports *a a*, having eyes or ears *b*, through which the parallel bars pass, and the swiveled hook *d*, connected to the coil *f*, substantially 75 as set forth.

HANS CHRISTIAN.
